UNITED STATES PATENT OFFICE.

HERBERT S. MILLS, OF CHICAGO, ILLINOIS.

FRAUD-PREVENTIVE FOR COIN-CONTROLLED APPARATUS.

SPECIFICATION forming part of Letters Patent No. 717,891, dated January 6, 1903.

Application filed April 7, 1902. Serial No. 101,712. (No model.)

To all whom it may concern:

Be it known that I, HERBERT S. MILLS, a citizen of the United States, residing at Chicago, in the county of Cook and State of Illinois, have invented a new and useful Improvement in Fraud-Preventives for Coin-Controlled Apparatus, of which the following is a specification.

My invention relates particularly to means for preventing the use of bogus coins in the operation of coin-controlled machines; and my primary object is to provide improved mechanism adapted to throw out or divert from the coin-chute bogus coins not possessing the qualities of the proper coins, the proper coins being permitted to continue in the coin-chute throughout its entire length, so as to reach the operative mechanism of the machine.

My invention is illustrated in its preferred embodiment in the accompanying drawings, in which—

Figure 1 represents a plate equipped with a coin-chute provided with the improved coin-ejecting device, one side of the coin-chute being removed to expose the coin-passage; and Fig. 2, a view of the same, the two views being employed, respectively, to illustrate the path of a proper coin and the path of a bogus coin.

The preferred construction is as follows: A represents a plate to which is secured a coin-chute A', surmounted by a device A² of common construction, which serves for the introduction of the coin into the coin-chute. The coin-chute has preferably an inclined portion a and a vertical portion a'. The vertical portion a' is provided with an enlargement or offset portion a², in which is mounted a swinging member a³. A chute-section a⁴ serves as a continuation of the offset portion of the chute and in use serves to conduct the coin to the operative mechanism of the machine to which the device here shown is applied. At the base of the chute-section a' is located an anvil or bounding-piece a⁵, which has an inclined top surface a⁶. The member a⁵ is separated from the upper portion of the chute-section a⁴ by a space a⁷. The member a³ is pivotally secured at a⁸ and has its lower end weighted and bearing normally against a pin a⁹, located slightly above the inclined

surface a⁶ and at sufficient distance therefrom to permit a bogus coin to pass through by way of the space a⁷.

The operation and manner of use will be understood readily from the foregoing detailed description. The mechanism here described is applied to any coin-controlled machine, the chute-section a⁴ serving to direct the coins to the machine proper, where they serve to control the operation of the machine. The coin is deposited at the device A² and fed into the chute A' in a manner well understood. If the proper coin is introduced, it strikes the inclined edge of the member a⁵, which member is preferably of tempered steel, and is caused to rebound and strike the member a³ with sufficient force to move the same to the dotted position shown in Fig. 1 and pass into the chute-section a⁴. If a disk of lead, wood, cardboard, or other relatively non-resilient material is employed, it will fail to bound over the pin a⁹ and will fall through the space a⁷, it being understood that the member a³ normally closes the entrance to the offset chute-section and possesses sufficient inertia to prevent it from being operatively moved by any but the proper coin. If an aluminium disk is employed, while it may bound up and strike the swinging plate a³ its light weight will give it insufficient momentum to allow it to pass by the plate into the offset chute-section.

Changes in details of construction within the spirit of my invention may be made. Hence no undue limitation is to be understood from the foregoing detailed description.

What I regard as new, and desire to secure by Letters Patent, is—

1. In means of the character described, the combination of a chute provided with an offset portion, a piece encountered by the coin during its fall and serving to hurl the coin laterally with reference to its path of descent, and means obstructing the offset portion of the chute and movable by a proper coin rebounding from said piece, for the purpose set forth.

2. In means of the character described, the combination of a chute-section through which coins may fall freely, an offset chute-section separated therefrom by a space through which bogus coins may pass freely, and a resilient

device for throwing the proper coins into said chute-section.

3. In means of the character described, the combination of a chute-section through which 5 coins may fall freely, an offset chute-section separated therefrom by a space through which bogus coins may pass freely, a resilient device for throwing the coins into said chute-section and means for obstructing the offset chute- 10 section and coin-operated, substantially as and for the purpose set forth.

4. In means of the character described, the combination of a chute-section through which 15 coins may fall freely, an offset chute-section separated therefrom by a space across which proper coins may bound, a resilient device for throwing the proper coins into said chute-section, and a coin-actuated pivoted obstruction for said offset chute-section.

20 5. In means of the character described, the combination of a chute-section through which the coins may fall to acquire momentum, a hard resilient member forming a bottom for said chute-section, and an offset chute-section 25 separated from said bottom by a space through which bogus coins may fall freely, for the purpose set forth.

6. In means of the character described, the combination of a chute-section through which 30 the coins may fall to acquire momentum, a

hard resilient member forming a bottom for said chute-section, an offset chute-section separated from said bottom by a space through which bogus coins may fall freely, and a coin-actuated pivoted obstruction for 35 said offset chute-section, substantially as and for the purpose set forth.

7. In means of the character described, the combination of a chute-section through which the coins may fall to acquire momentum, a 40 bounding-piece provided with an inclined surface, and an opposite chute-section provided with a coin-passage located above said inclined surface and separated therefrom by a space through which bogus coins may fall 45 freely.

8. In means of the character described, the combination of a chute-section through which the coins may fall to acquire momentum, a bounding-piece provided with an inclined 50 surface, an offset chute-section provided with a coin-passage located above said inclined surface and separated therefrom by a space through which bogus coins may fall freely, and a pivoted coin-actuated member guarding said passage.
